(57) **ABSTRACT**

A driver includes a first driving circuit and a second driving circuit. The second driving circuit includes a computation amplifier made up of a transistor with a breakdown voltage lower than a breakdown voltage of a transistor making up the first driving circuit, an output capacitor disposed between an output node of the computation amplifier and a signal supply line, and a first feedback capacitor disposed between an inverting input node of the computation amplifier and the signal supply line. The second driving circuit includes first to m-th voltage outputting capacitors including one end coupled to the inverting input node of the computation amplifier, and first to m-th voltage output circuits configured to output a voltage based on the gradation data to the other end of the first to m-th voltage outputting capacitors.

DRIVER, ELECTROOPTICAL DEVICE AND ELECTRONIC APPARATUS

The present application is based on, and claims priority from JP Application Serial Number 2022-096320, filed Jun. 15, 2022, the disclosure of which is hereby incorporated by reference herein in its entirety.

BACKGROUND

1. Technical Field

The present disclosure relates to a driver, an electrooptical device, an electronic apparatus and the like.

2. Related Art

JP-A-2016-80807 discloses a driver that includes a capacitance driving circuit and an amplifier circuit, and drives an electrooptic panel. After the start of capacitance driving for driving the electrooptic panel by the circuit capacitance driving circuit, the amplifier performs voltage driving for outputting the data voltage corresponding to the gradation data to the data voltage output terminal. In this manner, the voltage drop of the data line after the source line switch of the electrooptic panel is turned on from off is compensated by the amplifier circuit, and thus the reduction in accuracy of the data voltage in the capacitance driving is suppressed.

Since a high voltage is required for the driving depending on the type of the liquid crystal panel, a computation amplifier composed of a high-breakdown voltage transistor is used as the driving circuit for driving such a liquid crystal panel. However, since the mobility of a high-breakdown voltage transistor is low, it is difficult to achieve both the frequency response characteristic and the amplification factor of the computation amplifier. For example, it is necessary to increase the frequency response characteristic of the computation amplifier to increase the drive speed in accordance with higher resolution, but if the frequency response characteristic is increased while maintaining the amplification factor of the computation amplifier, the power consumption of the computation amplifier is undesirably increased.

SUMMARY

An aspect of the present disclosure relates to a driver including a first driving circuit configured to supply a data signal to a signal supply line of an electrooptic panel based on gradation data, and a second driving circuit including a computation amplifier, an output capacitor, a first feedback capacitor, first to m-th voltage outputting capacitors, and first to m-th voltage output circuits, and electrically coupled to the signal supply line, the computation amplifier being made up of a transistor with a breakdown voltage lower than a breakdown voltage of a transistor making up the first driving circuit, the output capacitor being disposed between an output node of the computation amplifier and the signal supply line, the first feedback capacitor being disposed between an inverting input node of the computation amplifier and the signal supply line, the first to m-th voltage outputting capacitors including one end coupled to the inverting input node of the computation amplifier, the first to m-th voltage output circuits being configured to output a

voltage based on the gradation data to the other end of the first to m-th voltage outputting capacitors, m being an integer of 2 or more.

In addition, another aspect of the present disclosure relates to an electrooptical device including the above-mentioned driver and the electrooptic panel.

In addition, still another aspect of the present disclosure relates to an electronic apparatus including the above-mentioned driver.

10

BRIEF DESCRIPTION OF THE DRAWINGS

FIG. 1 illustrates an exemplary configuration of an electrooptical device.

15 FIG. 2 illustrates a first specific configuration example of a driver.

FIG. 3 is a diagram illustrating a relationship between gradation data and data voltage.

20 FIG. 4 illustrates a first specific configuration example of a first driving circuit.

FIG. 5 illustrates a first specific configuration example of a second driving circuit.

25 FIG. 6 illustrates a first waveform example for describing operations of the first driving circuit and the second driving circuit.

FIG. 7 illustrates a second waveform example for describing operations of the first driving circuit and the second driving circuit.

30 FIG. 8 illustrates a third waveform example for describing operations of the first driving circuit and the second driving circuit.

FIG. 9 illustrates a second specific configuration example of a driver.

35 FIG. 10 is a diagram illustrating a relationship between gradation data, setting data and a data voltage.

FIG. 11 illustrates a second specific configuration example of the first driving circuit.

40 FIG. 12 illustrates a fourth waveform example for describing operations of the first driving circuit and the second driving circuit.

FIG. 13 illustrates a second specific configuration example of the second driving circuit.

FIG. 14 illustrates a relationship between gradation data and an output voltage of a data line driving circuit.

45 FIG. 15 illustrates a second specific configuration example of the second driving circuit.

FIG. 16 illustrates a fifth waveform example for describing operations of the first driving circuit and the second driving circuit.

50 FIG. 17 illustrates a sixth waveform example for describing operations of the first driving circuit and the second driving circuit.

FIG. 18 illustrates a configuration example of an electronic apparatus.

55

DESCRIPTION OF EXEMPLARY EMBODIMENTS

A preferred embodiment of the present disclosure is 60 elaborated below. The embodiment described below does not unduly limit the contents of the claims, and not all of the configurations described in the embodiment are essential configuration requirements.

1. Electrooptical Device

65 FIG. 1 illustrates a configuration example of an electrooptical device. An electrooptical device 400 includes a driver 100 and an electrooptic panel 200. While the electrooptic

device **400** of a phase expansion driving type is described as an example in the following description, this is not limitative, and the electrooptical device **400** may be of a demultiplexing driving type, for example.

The driver **100** drives the electrooptic panel **200** by outputting a data signal to a signal supply line of the electrooptic panel **200**. Note that the voltage written to one pixel at one time is referred to as data voltage. Further, when a plurality of pixels is driven in a time-series manner, the data voltage for each pixel is output as a time-series signal to the signal supply line, and this signal to the signal supply line is referred to as data signal.

The scan line driving circuit that drives the scan line of the electrooptic panel **200** may be included in the driver **100**, or may be provided outside the driver **100**. The driver **100** is an integrated circuit device in which a plurality of circuit elements is integrated on a semiconductor substrate, for example. The driver **100** includes a control circuit **40**, and first to k th data line driving circuits **DD1** to **DDk**. The k is an integer of 2 or more. Note that an exemplary case where $k=8$ is described below.

The control circuit **40** outputs corresponding gradation data to each data line driving circuit of the data line driving circuits **DD1** to **DD8**. In addition, the control circuit **40** outputs a control signal **ENBX** for controlling the data line switch to the electrooptic panel **200**.

The data line driving circuits **DD1** to **DD8** convert gradation data into a data voltage, and output the data voltage as output voltages **VQ1** to **VQ8** to signal supply lines **SPL1** to **SPL8** of the electrooptic panel **200**. The output voltages **VQ1** to **VQ8** change in accordance with time-series gradation data, and the signals of the changing output voltages **VQ1** to **VQ8** correspond to the above-described data signal.

The electrooptic panel **200** includes the first to eighth signal supply lines **SPL1** to **SPL8**, first to 1280th data line switches **SWEP1** to **SWEP1280**, and first to 1280th data lines **DL1** to **DL1280**. The number of data lines may be k . The t is an integer of 2 or more. Here, **WXGA** is taken as an example, and $t=160$ is set.

One end of each of data line switches **SWEP** $((j-1) \times k + 1)$ to **SWEP** $(j \times k)$ of the data line switches **SWEP1** to **SWEP1280** is coupled to the signal supply lines **SPL1** to **SPL8**. The j is an integer of 160 or smaller. For example, in the case of $j=1$, they are the data line switches **SWEP1** to **SWEP8**.

Each of the data line switches **SWEP1** to **SWEP1280** is composed of a TFT or the like, and is controlled based on the control signal **ENBX**, for example. TFT is an abbreviation of Thin Film Transistor. For example, the electrooptic panel **200** includes a switch control circuit not illustrated in the drawing, and the switch control circuit controls the data line switches **SWEP1** to **SWEP1280** on or off on the basis of the control signal **ENBX**.

The data line driving circuits **DD1** to **DD8** perform the driving 160 times in the horizontal scanning period, and, in the j th driving, data line switches **SWEP** $((j-1) \times k + 1)$ to **SWEP** $(j \times k)$ are on, and the other data line switches are off. In this manner, in the j th driving, the data lines **DL** $((j-1) \times k + 1)$ to **DL** $(j \times k)$ are driven. Regarding the data line driving circuit **DD1**, in the horizontal scanning period, the data line switches **SWEP1**, **SWEP2**, ..., **SWEP1273** are sequentially turned on, and the data line driving circuit **DD1** sequentially drives the data lines **DL1**, **DL2**, ..., **DL1273**.

2. First Embodiment

FIG. 2 illustrates a first specific configuration example of a driver. The driver **100** includes a data line driving circuit

110 and the control circuit **40**. The data line driving circuit **110** corresponds to any one of the data line driving circuits **DD1** to **DD8** of FIG. 1.

The data line driving circuit **110** includes a first driving circuit **60**, a second driving circuit **70**, a variable capacitance circuit **30**, and a detection circuit **50**. The control circuit **40** includes a processing circuit **42**, an interface circuit **44**, and a register circuit **48**.

The interface circuit **44** performs an interface process between a display controller **300** that controls the driver **100** and the driver **100**. The interface circuit **44** outputs, to the processing circuit **42**, gradation data **GD** [9:0] received from the display controller **300**. Note that the number of bits of the received gradation data may be arbitrary. The interface circuit **44** is an image interface circuit of an LVDS type, a parallel RGB type, a display port type or the like, for example. LVDS is an abbreviation of Low Voltage Differential Signaling.

In an initialization process at the time of power on of the driver **100** and the like, the processing circuit **42** determines setting data **CSW** [4:0] of the capacitance value of the variable capacitance circuit **30**, and stores the setting data **CSW** [4:0] in the register circuit **48**. In a normal operation for driving the electrooptic panel **200**, the processing circuit **42** sets the capacitance value of the variable capacitance circuit **30** with the setting data **CSW** [4:0] read from the register circuit **48**. In addition, on the basis of gradation data **GD** [9:0], the processing circuit **42** outputs gradation data **DTH** [10:0] to the first driving circuit **60**, and outputs gradation data **DTL** [10:0] to the second driving circuit **70**. In addition, the processing circuit **42** outputs a polarity inversion signal **FR** to the second driving circuit **70**. Note that depending on the configuration of the second driving circuit **70**, the input of the polarity inversion signal **FR** to the second driving circuit **70** may be omitted.

An output node **NVQ** is a node coupled to a data voltage output terminal **TVQ**, and the voltage of the output node **NVQ** is an output voltage **VQ**. The load capacitance of the data voltage output terminal **TVQ** is an electrooptic panel side capacitance **CP**.

The first driving circuit **60** supplies the charge corresponding to the gradation data **DTH** [10:0] to the output node **NVQ** through charge redistribution using the capacitor. When the charge is distributed to the variable capacitance circuit **30** and the electrooptic panel side capacitance **CP**, the output voltage **VQ** becomes a data voltage corresponding to the gradation data **DTH** [10:0]. The first driving circuit **60** is composed of a high-breakdown voltage process circuit element that can drive the electrooptic panel **200**. In an exemplary case where the electrooptic panel **200** is a liquid crystal panel of a high-temperature polysilicon type, the power source voltage of the first driving circuit **60** is about 15 V to 20 V, and the first driving circuit **60** is composed of a circuit element with a breakdown voltage higher than that of the power source voltage.

When there is an error in the charge output by the first driving circuit **60**, or the charge storage of the output node **NVQ** is slightly not viable, an error occurs between the output voltage **VQ** due to the charge output by the first driving circuit **60** and the target voltage corresponding to the gradation data **DTH** [10:0]. The second driving circuit **70** corrects the output voltage **VQ** to the target voltage through a feedback-control using a computation amplifier. In this case, since the error between the output voltage **VQ** and the target voltage is small, the amount of the charge output by the second driving circuit **70** can be small. By utilizing this, the computation amplifier is configured with a low-break-

down voltage process circuit element, while making DC-cut between the computation amplifier and the output node NVQ with a capacitor. As an example, the breakdown voltage of the low-breakdown voltage process is about $1/3$ to $1/10$ of the breakdown voltage of the high-breakdown voltage process. The second driving circuit 70 operates with a power source voltage lower than the breakdown voltage of the low-breakdown voltage process.

A capacitance value determination method of the variable capacitance circuit 30 and configuration examples of the variable capacitance circuit 30 and the detection circuit 50 are described below.

The detection circuit 50 compares a given detection voltage and the output voltage VQ, and outputs the result as a detection signal DET. The detection circuit 50 is a comparator, for example.

The processing circuit 42 outputs the gradation data DTH [10:0] corresponding to a given data voltage to a capacitor driving circuit 20. In this case, the above-mentioned given detection voltage is set to the same voltage as the given data voltage, which is an expected value of the output voltage VQ. The processing circuit 42 sequentially changes the capacitance value of the variable capacitance circuit 30 by sequentially changing the value of the setting data CSW [4:0]. The processing circuit 42 determines the capacitance value of the variable capacitance circuit 30 on the basis of the detection signal DET at each capacitance value. Specifically, the processing circuit 42 determines the capacitance value with which the output voltage VQ is set to the given detection voltage on the basis of the detection signal DET, and stores the setting data CSW [4:0] of the capacitance value in the register circuit 48.

The variable capacitance circuit 30 includes first to fifth adjusting capacitors and first to fifth adjusting switches. One end of the first adjusting switch is coupled to the output node NVQ, and the other end is coupled to one end of the first adjusting capacitor. The other end of the first adjusting capacitor is coupled to the ground node. The same applies to the second to fifth adjusting capacitors and the second to fifth adjusting switches. The capacitance values of the first to fifth adjusting capacitors are weighted in a binary manner. On-off control of the first adjusting switch is performed by the CSW [0]. Likewise, on-off control of the second to fifth adjusting switches is performed by the CSW [1] to CSW [4].

The first driving circuit 60, the second driving circuit 70, the variable capacitance circuit 30 and the detection circuit 50 are described in detail below.

FIG. 3 is a diagram illustrating a relationship between gradation data and data voltage.

The processing circuit 42 converts the input gradation data GD [9:0] into the gradation data DTH [10:0] and DTL [10:0]. More specifically, the processing circuit 42 converts the GD [9:0] of gradation values 0 to 1023 into the DTH [10:0] and DTL [10:0] of gradation values 1023 to 0 in the negative polarity drive, and converts the GD [9:0] of gradation values 0 to 1023 into the DTH [10:0] and DTL [10:0] of gradation values 1024 to 2047 in the positive polarity drive.

VSH=0 V is a low-potential side power source voltage of the first driving circuit 60. VDH=15 V is a high-potential side power source voltage of the first driving circuit 60. The common voltage supplied to the opposite electrode of the electrooptic panel 200 is VC=7.5 V. The data voltage supplied to the pixel is 7.5 V to 2.5 V in the negative polarity drive, and 7.5 V to 12.5 V in the positive polarity drive.

FIG. 4 illustrates a first specific configuration example of a first driving circuit. Note that in the following description,

as the reference symbol representing the capacitance value of the capacitor, the same reference symbol as the reference symbol of that capacitor is used. For example, the capacitance value of a capacitor C1 is represented by C1.

5 A capacitor circuit 10 includes first to n-th capacitors C1 to Cn. The capacitor driving circuit 20 includes first to n-th driving circuits DR1 to DRn. While an example of n=11 is described below, it suffices that n is an integer of 2 or more. It suffices that n is set to the same number as the number of bits of the gradation data DTH [10:0].

One end of the capacitor Ci is coupled to the output node NVQ, and the other end is coupled to a capacitor drive node NDRI. The i is an integer of 1 or more and n=11 or smaller. The capacitors C1 to C10 are capacitance values weighted in a binary manner. More specifically, the capacitance value of the capacitor Ci is $2^{(i-1)} \times C1$.

10 The processing circuit 42 outputs the ith bit DTH [i-1] of the gradation data DTH [10:0] to the input node of the driving circuit DRi. The driving circuit DRi outputs the first voltage level to the capacitor drive node NDRI when the bit DTH [i-1] is at the first logic level, and outputs the second voltage level to the capacitor drive node NDRI when the bit DTH [i-1] is at the second logic level. For example, the first logic level is “0”, the second logic level is “1”, the first voltage level is the low-potential side power source voltage VSH, and the second voltage level is the high-potential side power source voltage VDH. The driving circuit DRi is composed of a high-breakdown voltage process transistor, and operates with the power source voltages VDH and VSH. The driving circuit DRi is composed of a level shifter that level-shifts the input logic level to the output voltage level of the driving circuit DRi, and a buffer circuit that buffers the output of the level shifter.

15 20 25 30 35 When the driving circuits DR1 to DR11 drive the capacitors C1 to C11, charge redistribution occurs between the capacitors C1 to C11, the variable capacitance circuit 30, and the electrooptic panel side capacitance CP. As a result, the data voltage is output to the output node NVQ.

40 45 The electrooptic panel side capacitance CP is the sum of the capacitances seen from the data voltage output terminal TVQ. For example, the electrooptic panel side capacitance CP is obtained by adding up a substrate capacitance CP1, which is the parasitic capacitance of the printed board, and a panel capacitance CP2, which is the parasitic capacitance in the electrooptic panel 200. The printed board is a substrate on which the driver 100 is mounted and which is coupled to the electrooptic panel 200.

50 55 It is assumed that the sum of the capacitance values of the capacitors C1 to C11 is $C_{tot}=C1+C2+\dots+C11$, and the capacitance value of the variable capacitance circuit 30 is CF. As an example, the CF is set such that $C_{tot}/(CF+CP)=2$ holds. In this case, at the maximum gradation value 2047 of the DTH [10:0], $VQ=15 V \times \{C_{tot}/(C_{tot}+CF+CP)\}+2.5 V=10 V+2.5 V=12.5 V$ is obtained. At the minimum gradation value 0 of the DTH [10:0], $VQ=0 V \times \{C_{tot}/(C_{tot}+CF+CP)\}+2.5 V=0 V+2.5 V=2.5 V$ is obtained. In this manner, the same data voltage as the example of FIG. 3 is achieved.

60 65 FIG. 5 illustrates a first specific configuration example of the second driving circuit. The second driving circuit 70 includes a computation amplifier 71, an output capacitor CQ, a first feedback capacitor Cfa, a second feedback capacitor Cfb, an initialization switch SWR, first to m+1-th voltage outputting capacitors CB1 to CBm+1, and first to m+1-th voltage output circuits DB1 to DBm+1. Note that while an example of m=10 is described here, it suffices that m is an integer of 2 or more. In the first embodiment, it

suffices that $m+1$ is set to the same number as the number of bits of the gradation data DTL [10:0].

The computation amplifier 71 is composed of a low-breakdown voltage process transistor, and operates with a high-potential side power source voltage VDL and a low-potential side power source voltage VSL. While $VDL=1.8\text{ V}$ and $VSL=0\text{ V}$ are set in the following description, this is not limitative as long as the VDL is a voltage lower than the breakdown voltage of the low-breakdown voltage process. More specifically, the distance between the source and the drain of the transistor making up the first driving circuit 60 is greater than the distance between the source and the drain of the transistor making up the second driving circuit 70 including the computation amplifier 71. Alternatively, the film thickness of the gate insulating film of the transistor making up the first driving circuit 60 is greater than the film thickness of the gate insulating film of the transistor making up the second driving circuit 70 including the computation amplifier 71. It should be noted that while the above-mentioned configuration is an example of a configuration in which the breakdown voltage of the transistor differs, it suffices that the transistor of each driving circuit is configured such that the breakdown voltage of the transistor making up the second driving circuit 70 is lower than the breakdown voltage of the transistor making up the first driving circuit 60.

One end of the output capacitor C_Q is coupled to an output node $NAMQ$ of the computation amplifier 71, and the other end is coupled to the output node NVQ of the data line driving circuit 110. One end of the first feedback capacitor C_{fa} is coupled to an inverting input node NAN of the computation amplifier 71, and the other end is coupled to the output node NVQ of the data line driving circuit 110. One end of the second feedback capacitor C_{fb} is coupled to the inverting input node NAN of the computation amplifier 71, and the other end is coupled to the node of the low-potential side power source voltage VSL . Note that it suffices that the other end of the second feedback capacitor C_{fb} is coupled to a predetermined potential node to which a constant potential is supplied.

One end of the voltage outputting capacitor CB_p is coupled to the inverting input node NAN of the computation amplifier 71, and the other end is coupled to the output node of the voltage output circuit DB_p . The p is an integer of 1 or more and $m+1=11$ or smaller. The voltage outputting capacitors CB_1 to CB_{11} have capacitance values weighted in a binary manner. More specifically, the capacitance value of the voltage outputting capacitor CB_p is $2^{(p-1)} \times CB_1$.

The voltage output circuit DB_p outputs the first voltage level when a bit signal $XDTL[p-1]$, which is a logic inversion signal of the bit signal $DTL[p-1]$, is at the first logic level, and outputs the second voltage level when the bit signal $XDTL[p-1]$ is at the second logic level. For example, the first logic level is “0”, the second logic level is “1”, the first voltage level is the low-potential side power source voltage VSH , and the second voltage level is the high-potential side power source voltage VDH . The voltage output circuit DB_p is composed of a low-breakdown voltage process transistor, and operates with the power source voltages VDL and VSL . The voltage output circuit DB_p is a buffer circuit that buffers and outputs the input signal.

One end of the initialization switch SWR is coupled to the inverting input node NAN of the computation amplifier 71, and the other end is coupled to a node $NVREF$ to which a reference voltage $VREF$ is supplied. The non-inverting input node of the computation amplifier 71 is coupled to the node $NVREF$ to which the reference voltage $VREF$ is supplied.

The reference voltage $VREF$ is a voltage higher than the VSL and lower than the VDL . Here, the $VREF=0.9\text{ V}$ is set. The reference voltage $VREF$ is supplied to the node $NVREF$ from the voltage generation circuit not illustrated in the drawing included in the driver 100, for example. The initialization switch SWR is an analog switch, and is an N-type transistor, a P-type transistor or a transfer gate combining them, for example.

The initialization switch SWR is off during the pixel driving. At this time, the computation amplifier 71 performs a feedback control such that the voltage VFB of the inverting input node NAN of the computation amplifier 71 is the reference voltage $VREF=0.9\text{ V}$ by virtual short. As a result, bit signals the $XDTL$ to $XDTL[0]$ are set to 0 or 1 in accordance with the gradation data DTL [10:0], and thus the data voltage corresponding to the gradation data DTL [10:0] is output to the output node NVQ .

The capacitance value of each capacitor is described below. In the following description, the total capacitance of CB_1 to CB_{11} is described as $CB=CB_1+CB_2+\dots+CB_{11}$.

In the example of FIG. 3, the range of the output voltage VQ is 10 V . In this case, when all of the $XDTL$ to $XDTL[0]$ are changed from 1 to 0, i.e., when all of the output voltages of the voltage output circuits DB_1 to DB_{11} are changed from $VDL=1.8\text{ V}$ to $VSL=0\text{ V}$, it suffices that the output voltage VQ changes by 10 V , and therefore $CB/Cfa=10\text{ V}/1.8\text{ V}=50/9$ holds.

Conversely, the voltage change that is fed back to the inverting input node NAN of the computation amplifier 71 through the first feedback capacitor C_{fa} when the first driving circuit 60 changes the voltage of the output node NVQ by 10 V is referred to as Vfa . Here, it is assumed that $Vfa=1\text{ V}$ is set while it suffices that $Vfa=1.8\text{ V}$ holds as described later. In this case, since it suffices that 10 V is divided in 9:1 by C_{fa} and $C_{fb}+CB$, $(C_{fb}+CB)/C_{fa}=9$ holds.

Note that since the voltage change of the inverting input node NAN due to the change of the $XDTL$ to $XDTL[0]$ is 1.8 V at maximum, it suffices that $Vfa=1.8\text{ V}$ holds. When $Vfa \leq 1.8\text{ V}$ holds, it is possible to balance the voltage change of the inverting input node NAN due to the change of the $XDTL$ to $XDTL[0]$ and the voltage change of the inverting input node NAN when the voltage of the output node NVQ is changed by the first driving circuit 60. Specifically, as long as the voltage changes are ideally balanced, the voltage of the inverting input node NAN is maintained at $VFB=0.9\text{ V}$ even when the computation amplifier 71 does not output the charge, and it suffices that only when there is an error in the balance, the computation amplifier 71 outputs the charge for correcting that error.

The capacitance value of the output capacitor C_Q may be arbitrary as long as an output voltage AMQ of the computation amplifier 71 is set within the range of VSL to VDL . For example, the capacitance value of the output capacitor C_Q is set to about 1 to 10 times the sum of the capacitor circuit 10, the variable capacitance circuit 30 and the electrooptic panel side capacitance CP . As an example, in the case where the capacitance value of the output capacitor C_Q is four times the above-mentioned sum, an error of 0.1 V of the output voltage VQ can be compensated by changing the output voltage AMQ of the computation amplifier 71 by $0.1\text{ V} \times (5/4)=0.125\text{ V}$.

FIG. 6 illustrates a first waveform example for describing operations of the first driving circuit and the second driving circuit. It is assumed that the gradation values of the gradation data DTH [10:0] and DTL [10:0] change from 1024 to 1535 and to 1024. The target voltage corresponding to the gradation value 1535 is 10.0 V .

It is assumed that in the case where the second driving circuit **70** is not provided and the driving is performed only with the first driving circuit **60**, the output voltage VQ changes from 7.5 V to 9.9 V when the gradation value changes from 1024 to 1535. The difference from the target voltage 10.0 V is 0.1 V. An operation of the second driving circuit **70** in this case is described below.

When it is assumed that the output voltage VQ is changed by the first driving circuit **60** from 7.5 V to the target voltage 10 V, the voltage VFB of the inverting input node NAN of the computation amplifier **71** acts to change from 0.9 V to $0.9 V + (10 V - 7.5 V) / 10 = 1.15 V$. The increase is 0.25 V. At this time, the voltage outputting capacitors CB1 to CB11 and the voltage output circuits DB1 to DB11 of the second driving circuit **70** operates to reduce the voltage VFB of the inverting input node NAN by 0.25 V. In this manner, the change of the voltage VFB due to the first driving circuit **60** and the change of the voltage VFB due to the second driving circuit **70** are cancelled, thus causing no change at the voltage VFB=0.9 V.

However, when the output voltage VQ is changed by the first driving circuit **60** from 7.5 V to 9.9 V, the voltage VFB acts to change from 0.9 V to $0.9 V + (9.9 V - 7.5 V) / 10 = 1.14 V$. The increase is 0.24 V. Then, with the difference from the decrease 0.25 V due to the second driving circuit **70**, the voltage VFB= $0.9 V + (0.24 V - 0.25 V) = 0.89 V$ is obtained. The computation amplifier **71** sets the output voltage AMQ from V to $0.9 V + (10.0 V - 9.9 V) \times (5/4) = 1.025 V$ to set VFB=V. In this manner, the output voltage VQ is set to the target voltage 10.0 V, and the voltage VFB=0.9 V is obtained. In this manner, the computation amplifier **71** supplies only the charge corresponding to the error 0.1 V with respect to the target voltage 10 V to the output node NVQ through the output capacitor CQ.

FIG. 7 illustrates a second waveform example for describing operations of the first driving circuit and the second driving circuit. FIG. 7 illustrates a waveform example of a horizontal scanning period in a positive polarity drive period of a polarity inversion drive. While an example in which the gradation values 0, 127, ..., 1023 are sequentially written to nine pixels is described here, the number of pixels driven in the horizontal scanning period and the gradation value written to each pixel may be arbitrary.

The rising edge of a horizontal synchronization signal HSYNC is set as the start timing of the horizontal scanning period. After the horizontal scanning period is started, the processing circuit **42** outputs the DTH [9:0]=DTL [9:0]=0, and sets the DTH=DTL from 0 to 1. In this case, 0 is the low level and 1 is the high level. This corresponds to the DTH [10:0]=DTL [10:0]=1024, and therefore the output voltage VQ=7.5 V is obtained.

Next, the initialization switch SWR is turned from off to on, and from on to off. Here, off is the low level, and on is the high level. When the initialization switch SWR is on, the voltage VFB of the inverting input node NAN of the computation amplifier **71** is initialized to the reference voltage VREF=0.9 V. Note that the period in which the initialization of the voltage VFB is performed is referred to as initialization period. In FIG. 8, the period in which the initialization switch SWR is on corresponds to the initialization period.

Next, writing to the pixel is started. The processing circuit **42** sequentially outputs the DTH [9:0]=DTL [9:0] of the gradation values 0, 127, ..., 1023. As a result, the output voltage VQ sequentially changes from 7.5 V to 12.5 V. Note that while the gradation value for which the voltage range is

easy to understand is exemplified here, the gradation value written to each pixel may be arbitrary as described above.

FIG. 8 illustrates a third waveform example for describing operations of the first driving circuit and the second driving circuit. FIG. 8 illustrates a waveform example of a horizontal scanning period in a negative polarity drive period in a polarity inversion drive.

After the horizontal scanning period is started, the processing circuit **42** outputs the DTH [9:0]=DTL [9:0]=0, and sets the DTH=DTL from 0 to 1. This corresponds to the DTH [10:0]=DTL [10:0]=1024, and therefore the output voltage VQ=7.5 V is obtained.

Next, the initialization switch SWR from off to on, and from on to off. When the initialization switch SWR is on, the voltage VFB of the inverting input node NAN of the computation amplifier **71** is initialized to the reference voltage VREF=0.9 V.

Next, the processing circuit **42** sets DTH=DTL from 1 to 0. As a result, DTH [10:0]=DTL [10:0]=0 is set, and the output voltage VQ changes from 7.5 V to 2.5 V.

Next, writing to the pixel is started. The processing circuit **42** sequentially outputs the DTH [9:0]=DTL [9:0] of the gradation values 0, 127, ..., 1023. As a result, the output voltage VQ sequentially changes from 2.5 V to 7.5 V. Note that while the gradation value for which the voltage range is easy to understand is exemplified here, the gradation value written to each pixel may be arbitrary.

Note that while the DTH [10:0]=DTL [10:0] is described above, the DTH [10:0]≠DTL [10:0] may be set. For example, the DTH [10:0]≠DTL [10:0] may be set with correction data added to the gradation data DTH [10:0]. The correction data is, for example, data for correcting the excess/deficient electric charge amount. The excess/deficient electric charge amount is excess or deficiency between the charge output by the first driving circuit **60** with the gradation data DTH [10:0] to which the correction data is not added, and the charge required for setting the output voltage VQ to the target voltage. The correction data is data obtained by converting the excess/deficient electric charge amount to a gradation value. Adding correction data to the gradation data DTH [10:0] can reduce the error between the output voltage VQ due to the charge output by the first driving circuit **60** and the target voltage corresponding to the gradation data DTH [10:0]. In the case where such a correction is performed, when there is still an error between the output voltage VQ and the target voltage even after the correction, the second driving circuit **70** corrects the error through a feedback control using the computation amplifier **71**.

In the above-mentioned embodiment, the driver **100** includes the first driving circuit **60** that supplies a data signal to the signal supply line of the electrooptic panel **200** on the basis of the gradation data, and the second driving circuit **70** electrically coupled to the signal supply line. The second driving circuit **70** includes the computation amplifier **71**, the output capacitor CQ, the first feedback capacitor Cfa, the first to m-th voltage outputting capacitors CB1 to CBm, and the first to m-th voltage output circuits DB1 to DBm. Note that in the first embodiment, the CB1 to CB10 correspond to the CB1 to CBm. Note that it suffices that $m \geq 2$ holds. The computation amplifier **71** is composed of a transistor with a breakdown voltage lower than the breakdown voltage of the transistor making up the first driving circuit **60**. The output capacitor CQ is provided between the output node NAMQ of the computation amplifier **71** and the signal supply line. The first feedback capacitor Cfa is provided between the inverting input node NAN of the computation amplifier **71**

11

and the signal supply line. One ends of the first to m-th voltage outputting capacitors CB1 to CBm are coupled to the inverting input node NAN of the computation amplifier 71. The first to m-th voltage output circuits DB1 to DBm output the voltage based on the gradation data to the other ends of the first to m-th voltage outputting capacitors CB1 to CBm.

According to this embodiment, the output node NAMQ of the computation amplifier 71 and the signal supply line are coupled by the output capacitor CQ, and the inverting input node NAN of the computation amplifier 71 and the signal supply line are coupled by the first feedback capacitor Cfa. In this manner, the computation amplifier 71 and the signal supply line are DC disconnected, and thus the computation amplifier 71 can be composed of a transistor with a breakdown voltage lower than the breakdown voltage of the transistor making up the first driving circuit 60.

In addition, since the computation amplifier 71 is composed of a transistor with a breakdown voltage lower than the breakdown voltage of the transistor making up the first driving circuit 60, the computation amplifier 71 can be composed of a transistor with high mobility. In this manner, the frequency response characteristic and the amplification factor of the computation amplifier can both be achieved. For example, regarding the necessity to increase the frequency response characteristic of the computation amplifier to increase the drive speed in accordance with higher resolution, the frequency response characteristic can be increased while maintaining the amplification factor of the computation amplifier, and the power consumption of the computation amplifier can be suppressed.

Note that the electrical coupling is coupling that enables transmission of an electric signal and transmission of information using an electric signal. The electrical coupling may be coupling via an active element and the like.

In addition, in this embodiment, the reference voltage VREF is input to the non-inverting input node of the computation amplifier 71.

According to this embodiment, the reference voltage VREF is input to the non-inverting input node of the computation amplifier 71, and the first to m-th voltage output circuits DB1 to DBm output the voltage based on the gradation data to the other ends of the first to m-th voltage outputting capacitors CB1 to CBm, and thus, the second driving circuit 70 can output the voltage corresponding to the gradation data. That is, the second driving circuit 70 functions as a D/A conversion circuit that D/A-converts the gradation data.

In addition, in this embodiment, the second driving circuit 70 includes the second feedback capacitor Cfb provided between the inverting input node NAN of the computation amplifier 71 and a predetermined potential node.

According to this embodiment, the voltage of the signal supply line is divided by the first feedback capacitor Cfa and the second feedback capacitor Cfb and fed back to the inverting input node NAN of the computation amplifier 71. In this manner, the voltage change 1 V smaller than the voltage 10 V of the signal supply line change is fed back to the inverting input node NAN of the computation amplifier 71, and thus the computation amplifier 71 can be composed of a transistor with a breakdown voltage lower than the breakdown voltage of the transistor making up the first driving circuit 60.

In addition, in this embodiment, the second driving circuit 70 includes the m+1-th voltage outputting capacitor CBm+1 including one end electrically coupled to the inverting input node NAN of the computation amplifier 71, and the m+1-th

12

voltage output circuit DBm+1 that outputs the voltage based on the gradation data to the other end of the m+1-th voltage outputting capacitor CBm+1. Note that in the first embodiment, the CB11 corresponds to the CBm+1.

According to this embodiment, the first to m+1-th voltage output circuits DB1 to DBm+1 output the voltage based on the gradation data to the other ends of the first to m+1-th voltage outputting capacitors CB1 to CBm+1, and thus the second driving circuit 70 can output the voltage corresponding to the gradation data. As described with FIG. 3, the gradation data of m+1=11 bits combining the negative polarity and the positive polarity is obtained by extending the gradation data of m=10 bits by 1 bit, and thus the second driving circuit 70 can output the gradation voltage of the negative polarity and positive polarity.

In addition, in this embodiment, the total capacitance of the second feedback capacitor Cfb and the first to m+1-th voltage outputting capacitors CB1 to CBm+1 is greater than the capacitance of the first feedback capacitor Cfa. For example, in the first embodiment, (Cfb+CB)/Cfa=9 holds in the case of CB=CB1+CB2+...+CB11.

The gain fed back by the voltage change of the output node NVQ to the inverting input node NAN of the computation amplifier 71 is Cfa/(Cfa+Cfb+CB). According to this embodiment, since the feedback gain is smaller than 1/2, the voltage range that is fed back to the inverting input node NAN of the computation amplifier 71 is smaller than 1/2 of the voltage range of the signal supply line. In this manner, the computation amplifier 71 can be composed of a transistor with a breakdown voltage lower than the breakdown voltage of the transistor making up the first driving circuit 60.

In addition, in this embodiment, the distance between the source and the drain of the transistor making up the first driving circuit 60 is greater than the distance between the source and the drain of the transistor making up the second driving circuit 70. Alternatively, the film thickness of the gate insulating film of the transistor making up the first driving circuit 60 is greater than the film thickness of the gate insulating film of the transistor making up the second driving circuit 70.

According to this embodiment, the transistor making up the second driving circuit 70 including the computation amplifier 71 can be composed of a transistor with a breakdown voltage lower than the breakdown voltage of the transistor making up the first driving circuit 60.

In addition, in this embodiment, the first to m-th voltage output circuits DB1 to DBm are composed of a transistor with a breakdown voltage lower than the breakdown voltage of the transistor making up the first driving circuit 60.

As described above, in this embodiment, the voltage change fed back to the inverting input node NAN of the computation amplifier 71 is Vfa=1 V≤1.8 V=VDL. In this manner, the first to m-th voltage output circuits DB1 to DBm can be composed of a low-breakdown voltage transistor. The use of a low-breakdown voltage transistor enables faster pixel drive and smaller driver area.

Note that the m+1-th voltage output circuit DBm+1 may be composed of a transistor with a breakdown voltage lower than the breakdown voltage of the transistor making up the first driving circuit 60, or may be composed of a transistor with the same breakdown voltage as that of the transistor making up the first driving circuit 60 as described later in third embodiment.

In addition, in this embodiment, the driver 100 includes the initialization switch SWR. The initialization switch SWR is turned on in the initialization period, and supplies

the reference voltage VREF to the inverting input node NAN of the computation amplifier 71.

According to this embodiment, the inverting input node NAN of the computation amplifier 71 is initialized to the reference voltage VREF in the initialization period, and thereafter maintained at the reference voltage VREF through virtual short. In this manner, in the case where the output voltage VQ output by the first driving circuit 60 is shifted from the target voltage, the voltage of the inverting input node NAN of the computation amplifier 71 is shifted from the reference voltage VREF, and this shift is corrected by the computation amplifier 71, thus setting the output voltage VQ to the target voltage.

In addition, in this embodiment, the first driving circuit 60 includes the capacitor driving circuit 20 and the capacitor circuit 10. The capacitor driving circuit 20 outputs first to n-th capacitor drive voltages corresponding to the gradation data DTH [10:0] to first to n-th capacitor driving nodes NDR1 to NDRn. Here, n is an integer of 2 or more. The capacitor circuit 10 includes the first to n-th capacitors C1 to Cn provided between the signal supply line and the first to n-th capacitor driving nodes NDR1 to NDRn.

According to this embodiment, the capacitor driving circuit 20 outputs the first to n-th capacitor drive voltages corresponding to the gradation data DTH [10:0], and thus the first to n-th capacitors C1 to Cn output the charge of the electric charge amount corresponding to the gradation data DTH [10:0] to the signal supply line. In this manner, the voltage corresponding to the gradation data DTH [10:0] is output to the signal supply line. Since this driving is not feedback-controlled, errors may be caused between the voltage output through the driving and the target voltage. The second driving circuit 70 can correct the error through a feedback-control.

3. Second Embodiment

FIG. 9 illustrates a second specific configuration example of a driver. In this configuration example, the data line driving circuit 110 includes the first driving circuit 60 and the second driving circuit 70. In addition, the processing circuit 42 outputs setting data DP [9:0], DN [9:0] for setting the driving capability of the first driving circuit 60 on the basis of the gradation data GD [9:0]. Note that the configuration and operation of the second driving circuit 70 are the same as in the first embodiment, and therefore the configuration and operation of the first driving circuit 60 are mainly described below.

FIG. 10 is a diagram illustrating a relationship between gradation data, setting data and a data voltage. The relationship between the gradation data GD [9:0], the gradation data DTH [10:0] and the data voltage are the same as in FIG. 3.

It is assumed that a certain pixel is driven by a gradation value DTH1, that the next pixel is driven by a gradation value DTH2, and that DTH2-DTH1>0 holds. In this case, the processing circuit 42 outputs DP [9:0]=1DTH2-DTH11, DN [9:0]=0. It is assumed that a certain pixel is driven by a gradation value DTH3, that the next pixel is driven by a gradation value DTH4, and that DTH4-DTH3<0 holds. In this case, the processing circuit 42 outputs DP [9:0]=0, DN [9:0]=1DTH4-DTH31. FIG. 10 illustrates an example of the positive polarity drive, but the same applies to the negative polarity drive.

Note that since DTH cancels when the difference is taken, the DP [9:0] and DN [9:0] can be directly computed from the gradation data GD [9:0], not through DTH [10:0].

FIG. 11 illustrates a second specific configuration example of the first driving circuit. In this configuration example, the first driving circuit 60 includes a first driving transistor group TRG1 and a second driving transistor group TRG2.

The first driving transistor group TRG1 includes P-type transistors TP1 to TP10 coupled in parallel between the node of the high-potential side power source voltage VDH and the output node NVQ. A bit signal XDP [0] is input to the gate 10 of the P-type transistor TP1. Likewise, bit signals XDP [1] to XDP [9] are input to the gates of the P-type transistors TP2 to TP10. XDP [9:0] is data obtained through the logic inversion of each bit of the DP [9:0]. The driving capabilities of the P-type transistors TP1 to TP10 are binary weighted. Specifically, the driving capability of P-type transistor TPi is $2^{(i-1)}$ times the driving capability of the P-type transistor TP1. The driving capability is adjusted by the gate width of the transistor or the number of the unit transistors coupled in parallel, for example.

The second driving transistor group TRG2 includes N-type transistors TN1 to TN10 coupled in parallel between the output node NVQ and the low-potential side power source voltage VSH. A bit signal DN [0] is input to the gate 25 of the N-type transistor TN1. Likewise, bit signals DN [1] to DN [9] are input to the gates of the N-type transistors TN2 to TN10. The driving capabilities of the N-type transistors TN1 to TN10 are binary weighted. Specifically, the driving capability of the N-type transistor TNi is $2^{(i-1)}$ times the driving capability of the N-type transistor TN1.

For example, the current that is supplied when the P-type transistor TP1 is on is referred to as I_{TP1} , and the on period in which one pixel is driven is referred to as t_{on} . The charge supplied by the P-type transistor TP1 to the output node 35 NVQ is $I_{TP1} \times t_{on}$, and the change of the output voltage VQ due to the charge is $(I_{TP1} \times t_{on})/CP$. I_{TP1} is set, i.e., the driving capability of the P-type transistor TP1 is set such that this voltage change corresponds to 1 LSB.

FIG. 12 illustrates a fourth waveform example for 40 describing operations of the first driving circuit and the second driving circuit. FIG. 12 illustrates a waveform example of the horizontal scanning period in the positive polarity drive period.

After the horizontal scanning period is started, the processing circuit 42 outputs the DTL [9:0]=DP [9:0]=DN 45 [9:0]=0, and sets the DTL from 0 to 1. This corresponds to the DTL [10:0]=1024, and therefore the output voltage VQ=7.5 V is obtained.

Next, the initialization switch SWR from off to on, and 50 from on to off. When the initialization switch SWR is on, the voltage VFB of the inverting input node NAN of the computation amplifier 71 is initialized to the reference voltage VREF=0.9 V.

Next, writing to the pixel is started. The processing circuit 55 42 sequentially outputs the DTL [9:0] of the gradation values 0, 127, . . . , 1023, and sequentially outputs the DP [9:0]=0, 127, 128, . . . , 128. As a result, the output voltage VQ sequentially changes from 7.5 V to 12.5 V. Note that while FIG. 12 illustrates an example of DP [9:0]>0 and DN 60 [9:0]=0, DP [9:0]=0 and DN [9:0]>0 are obtained in the case where the gradation value of the DTL [9:0] decreases. Note that while the gradation value for which the voltage range is easy to understand is exemplified here, the gradation value written to each pixel may be arbitrary.

For the negative polarity drive period, the illustration of the waveform is omitted. In the negative polarity drive period, the waveforms of the SWR, DTL [9:0], DP [9:0], and

DN [9:0] are the same as in FIG. 12. The waveforms of the DTL and VQ are the same as in FIG. 8.

In the above-mentioned embodiment, the driver 100 includes the control circuit 40 that controls the first driving circuit 60. The first driving circuit 60 includes the first driving transistor group TRG1 provided between the signal supply line and the node to which the high-potential side power source voltage VDH is supplied, and the second driving transistor group TRG2 provided between the signal supply line and the node to which the low-potential side power source voltage VSH is supplied. The control circuit 40 performs on-off control of each transistor of the first driving transistor group TRG1 or each transistor of the second driving transistor group TRG2 on the basis of the gradation data GD [9:0].

According to this embodiment, of the first driving transistor group TRG1 or the second driving transistor group TRG2, the transistor turned on based on the gradation data GD [9:0] outputs the charge of the electric charge amount corresponding to the gradation data GD [9:0] to the signal supply line. As a result, the voltage corresponding to the gradation data GD [9:0] is output to the signal supply line. Since this driving is not feedback-controlled, errors may be caused between the voltage output through the driving and the target voltage. The second driving circuit 70 can correct the error through a feedback-control.

4. Third Embodiment

In the third embodiment, the configuration and operation of the first driving circuit 60 are the same as in the first embodiment or the second embodiment. For the configuration and operation of the second driving circuit 70, differences from the first embodiment are mainly described below.

FIG. 13 illustrates a second specific configuration example of the second driving circuit. In this configuration example, the processing circuit 42 outputs the gradation data DTM [9:0] on the basis of the gradation data GD [9:0]. Bit signals XDTM [9], XDTM [8], ..., XDTM [0], which are logic inversion signals of the bit signals DTM [9], DTM [8], ..., DTM [0], are input to the voltage output circuits DB10, DB9, ..., DB1. In addition, the processing circuit 42 outputs the polarity inversion signal FR representing the drive polarity. A signal XFR, which is a logic inversion signal of the polarity inversion signal FR, is input to the voltage output circuit DB11.

FIG. 14 illustrates a relationship between an output voltage of the data line driving circuit and the gradation data. In the positive polarity drive, the processing circuit 42 sets the DTM [9:0]=GD [9:0], and the second driving circuit 70 outputs the output voltage VQ=7.5 V to 15 V for the DTM [9:0]=0 to 1023. In the negative polarity drive, the processing circuit 42 sets the DTM [9:0]=XGD [9:0], and the second driving circuit 70 outputs the output voltage VQ=2.5 V to 7.5 V for the DTM [9:0]=0 to 1023.

In this configuration example, when the first driving circuit 60 changes the voltage of the output node NVQ by 5 V, the voltage change that is fed back to the inverting input node NAN of the computation amplifier 71 through the first feedback capacitor Cfa is Vfa=1 V. In this case, since it suffices that 10 V is divided in 4:1 by Cfa and Cfb+CB, (Cfb+CB)/Cfa=4 holds. Note that it suffices that Vfa≤1.8 V holds as described above. In addition, in this configuration example, since it suffices that the voltage outputting capacitor CB11 and the voltage output circuit DB11 generate a

voltage shift corresponding to Vfa=1 V/2=0.5 V, the capacitance value of the voltage outputting capacitor CB11 is CB11=CB10.

FIG. 15 illustrates a second specific configuration example of the second driving circuit. In this configuration example, the second driving circuit 70 further includes level shifters LSB11 and LSB10. Note that while an exemplary case where the level shifter is provided at the preceding stage of the voltage output circuits DB11 and DB10 is described here, this is not limitative. For example, the level shifter may be provided only at the preceding stage of voltage output circuit DB11, or the level shifter may be provided at the preceding stage of a predetermined number of voltage output circuits on the higher-level side among the voltage output circuits DB10 to DB1.

The level shifter LSB11 level-shifts the signal XFR to the power source voltages VDH and VSH of the high-breakdown voltage process. Specifically, when the signal XFR is at the low level, i.e., VSL=0 V, the level shifter LSB11 outputs a signal of VSH=0 V, and the voltage output circuit DB11 outputs a signal of VSH=0 V to the other end of the voltage outputting capacitor CB11. When the signal XFR is at the high level, i.e., VDL=1.8 V, the level shifter LSB11 outputs a signal of VDH=V, and the voltage output circuit DB11 outputs a signal of VDH=15 V to the other end of the voltage outputting capacitor CB11.

The level shifter LSB10 level-shifts the bit signal XDTM [9] to the power source voltages VDH and VSH of the high-breakdown voltage process. Specifically, when the signal XDTM [9] is at the low level, i.e., VSL=0 V, the level shifter LSB10 outputs a signal of VSH=0 V, and the voltage output circuit DB10 outputs a signal of VSH=0 V to the other end of the voltage outputting capacitor CB10. When the signal XDTM [9] is at the high level, i.e., VDL=1.8 V, the level shifter LSB10 outputs a signal of VDH=15 V, and the voltage output circuit DB10 outputs a signal of VDH=15 V to the other end of the voltage outputting capacitor CB10.

Since the amplitude of the voltage output by the voltage output circuits DB11 and DB10 is 15 V, the capacitance value of the voltage outputting capacitors CB11 and CB10 can be set to 1.8 V/15 V=3/25 times that of the second specific configuration example.

FIG. 16 illustrates a fifth waveform example for describing operations of the first driving circuit and the second driving circuit. FIG. 16 illustrates a waveform example of the horizontal scanning period in the positive polarity drive period.

After the horizontal scanning period is started, the processing circuit 42 outputs the DTH [9:0]=0 and the DTM [9:0]=512, and sets the DTH from 0 to 1. In this case, the output voltage VQ=7.5 V is obtained.

Next, after setting the signal XFR from the low level to the high level, the processing circuit 42 turns the initialization switch SWR from off to on, and from on to off. When the signal XFR is at the high level and the initialization switch SWR is on, the voltage VFB of the inverting input node NAN of the computation amplifier 71 is initialized to the reference voltage VREF=0.9 V. Next, the processing circuit 42 sets the signal XFR from the high level to the low level, and sets the DTM [9:0] from 512 to 0, for example. Since the XFR is changed from the high level to the low level, the XDTM [9] is changed from the low level to the high level, and CB11=CB10 holds as described above, the charge is canceled and the output voltage VQ of the second driving circuit 70 does not change. Note that in FIG. 16, the period until the signal XFR is changed from the high level

to the low level after the initialization switch SWR is turned on from off corresponds to the initialization period.

Next, writing to the pixel is started. The processing circuit 42 sequentially outputs the DTH [9:0]=DTM [9:0] of the gradation values 0, 127, . . . , 1023. As a result, the output voltage VQ sequentially changes from 7.5 V to 12.5 V. Note that while the gradation value for which the voltage range is easy to understand is exemplified here, the gradation value written to each pixel may be arbitrary.

In the third embodiment, the feedback gain from the output voltage VQ to the voltage VFB of the inverting input node NAN of the computation amplifier 71 is $\frac{1}{2}$. Specifically, the change 5 V of the output voltage VQ is fed back to the inverting input node NAN of the computation amplifier 71 as a voltage change of $V_{fa}=1$ V. This $V_{fa}=1$ V is canceled by the input/output charge of the voltage outputting capacitors CB1 to CB10. On the other hand, in the first embodiment, the feedback gain is $\frac{1}{10}$, and therefore the change 5 V of the output voltage VQ is fed back as a voltage change of $V_{fa}=0.5$ V. Likewise, this $V_{fa}=0.5$ V is canceled by the input/output charge of the voltage outputting capacitors CB1 to CB10. In view of the foregoing, it can be said that in the third embodiment, data of bits is substantially D/A-converted into the voltage range of 1 V, and that in the first embodiment, data of 10 bits is substantially D/A-converted into the voltage range of 0.5 V. Thus, the voltage step per LSB is larger in the third embodiment, and the accuracy of the D/A conversion can be improved.

FIG. 17 illustrates a sixth waveform example for describing operations of the first driving circuit and the second driving circuit. FIG. 17 illustrates a waveform example of the horizontal scanning period in the negative polarity drive period.

After the horizontal scanning period is started, the processing circuit 42 outputs the DTH [9:0]=0 and the DTM [9:0]=512, and sets the DTH from 0 to 1. In this case, the output voltage VQ=7.5 V is obtained.

Next, after setting the signal XFR from the high level to the low level, the processing circuit 42 turns the initialization switch SWR from off to on, and from on to off. When the signal XFR is at the low level and the initialization switch SWR is on, the voltage VFB of the inverting input node NAN of the computation amplifier 71 is initialized to the reference voltage VREF=0.9 V. Next, the processing circuit 42 sets the signal XFR from the low level to the high level, sets the DTH from 1 to 0, and sets the DTH [9:0]=DTM [9:0] to 1023, for example. In this case, since both the output voltage of the first driving circuit 60 and the output voltage of the second driving circuit 70 do not change, the voltage VQ of the output node NVQ does not change.

Next, writing to the pixel is started. After setting the DTH from 1 to 0, the processing circuit 42 sequentially outputs the DTH [9:0]=DTM [9:0] of the gradation values 1023, 895, . . . , 0. In this manner, the output voltage VQ sequentially changes from 7.5 V to 2.5 V. Note that while the gradation value for which the voltage range is easy to understand is exemplified here, the gradation value written to each pixel may be arbitrary.

Note that the accuracy of the D/A conversion can be improved in comparison with the first embodiment as in the case of the positive polarity drive described above.

In the above-mentioned embodiment, the second driving circuit 70 includes the m+1-th voltage outputting capacitor CBm+1 including one end electrically coupled to the inverting input node NAN of the computation amplifier 71, and the m+1-th voltage output circuit DBm+1 that outputs the

voltage based on the polarity inversion signal FR to the other end of the m+1-th voltage outputting capacitor CBm+1. Note that the CB11 corresponds to the CBm+1 in the third embodiment. In addition, since a logic inversion signal of the polarity inversion signal FR is input to the CB11, the CB11 outputs the voltage based on the polarity inversion signal FR.

According to this embodiment, the m+1-th voltage output circuit DBm+1 outputs the voltage based on the polarity inversion signal FR, and thus the charge based on the polarity inversion signal FR is output to the inverting input node NAN of the computation amplifier 71 from the m+1-th voltage outputting capacitor CBm+1. In this manner, the feedback gain from the output node NVQ to the inverting input node NAN of the computation amplifier 71 can be made smaller than in the first embodiment as described above, and thus the accuracy of the D/A conversion of the second driving circuit 70 and the like can be achieved.

In addition, in this embodiment, the total capacitance of the second feedback capacitor Cfb and the first to m+1-th voltage outputting capacitors CB1 to CBm+1 is greater than the capacitance of the first feedback capacitor Cfa. For example, in the first embodiment, when $CB=CB1+CB2+\dots+CB11$ is set, $(Cfb+CB)/Cfa=4$ holds.

The gain fed back by the voltage change of the output node NVQ to the inverting input node NAN of the computation amplifier 71 is $Cfa/(Cfa+Cfb+CB)$. According to this embodiment, since the feedback gain is smaller than $\frac{1}{2}$, the voltage range that is fed back to the inverting input node NAN of the computation amplifier 71 is smaller than $\frac{1}{2}$ of the voltage range of the signal supply line. In this manner, the computation amplifier 71 can be composed of a transistor with a breakdown voltage lower than the breakdown voltage of the transistor making up the first driving circuit 60.

5. Electronic Apparatus

FIG. 18 illustrates a configuration example of an electronic apparatus including the driver of the embodiment. The electronic apparatus of the embodiment may be various electronic apparatuses equipped with a display device. For example, the electronic apparatus is a projector, a television device, an information processing device, a mobile information terminal, a car navigation system, a mobile game terminal, or the like.

An electronic apparatus 500 includes the electrooptical device 400, the display controller 300, a processing device 310, a storage unit 320, a user interface unit 330, and a data interface unit 340. An electrooptical device 400 includes a driver 100 and an electrooptic panel 200.

The electrooptic panel 200 is a matrix-type liquid crystal display panel, for example. Alternatively, the electrooptic panel 200 may be an EL display panel using a self-luminous element. EL is an abbreviation of Electro-Luminescence. The user interface unit 330 is an interface unit that receives various operations from the user. For example, it is composed of a button, a mouse, a keyboard, a touch panel equipped in the electrooptic panel 200 and the like. The data interface unit 340 is an interface unit for inputting and outputting image data or control data. For example, it is a wired communication interface of USB or the like, or a radio communication interface of wireless LAN or the like. The storage unit 320 stores the image data input from the data interface unit 340. Alternatively, the storage unit 320 functions as a working memory of the processing device 310 or the display controller 300. The processing device 310 per-

forms the control process of each unit of the electronic apparatus and various data processes. The processing device 310 is a processor such as a microcomputer or a CPU. The display controller 300 performs the control process of the driver 100. For example, the display controller 300 converts image data transferred from the data interface unit 340 or the storage unit 320 into a format that can be received by the driver 100, and outputs the converted image data to the driver 100. The driver 100 drives the electrooptic panel 200 on the basis of the image data transferred from the display controller 300.

The driver of the embodiment described above includes a first driving circuit configured to supply a data signal to a signal supply line of an electrooptic panel based on gradation data, and a second driving circuit electrically coupled to the signal supply line. The second driving circuit includes the computation amplifier being made up of a transistor with a breakdown voltage lower than a breakdown voltage of a transistor making up the first driving circuit, and the output capacitor being disposed between an output node of the computation amplifier and the signal supply line. In addition, the second driving circuit includes the first feedback capacitor being disposed between an inverting input node of the computation amplifier and the signal supply line, and the first to m-th voltage outputting capacitors including one end coupled to the inverting input node of the computation amplifier. M is an integer of 2 or more. In addition, the second driving circuit includes the first to m-th voltage output circuits that output the voltage based on the gradation data to the other end of the first to m-th voltage outputting capacitors.

According to this embodiment, with the output capacitor and the first feedback capacitor, the computation amplifier and the signal supply line are DC disconnected. In this manner, the computation amplifier can be composed of a transistor with a breakdown voltage lower than the breakdown voltage of the transistor making up the first driving circuit. In addition, with the computation amplifier composed of the low breakdown voltage transistor, the computation amplifier can be composed of a transistor with high mobility. In this manner, the frequency response characteristic and the amplification factor of the computation amplifier can both be achieved. In addition, as a result, the power consumption of the computation amplifier can be suppressed.

In addition, in this embodiment, a reference voltage may be input to a non-inverting input node of the computation amplifier.

According to this embodiment, the reference voltage is input to the non-inverting input node of the computation amplifier, and the first to m-th voltage output circuits output the voltage based on the gradation data to the other end of the first to m-th voltage outputting capacitors, and thus, the second driving circuit can output the voltage corresponding to the gradation data. That is, the second driving circuit functions as a D/A conversion circuit that D/A-converts the gradation data.

In addition, in this embodiment, the second driving circuit may include a second feedback capacitor disposed between the inverting input node of the computation amplifier and a predetermined potential node.

According to this embodiment, the voltage of the signal supply line is divided by the first feedback capacitor and the second feedback capacitor and fed back to the inverting input node of the computation amplifier. In this manner, a voltage change smaller than the voltage change of the signal supply line is fed back to the inverting input node of the

computation amplifier, and thus the computation amplifier can be composed of a transistor with a breakdown voltage lower than the breakdown voltage of the transistor making up the first driving circuit.

5 In addition, in this embodiment, the second driving circuit may include an m+1-th voltage outputting capacitor including one end electrically coupled to the inverting input node of the computation amplifier; and an m+1-th voltage output circuit configured to output the voltage based on the gradation data to the other end of the m+1-th voltage outputting capacitor.

According to this embodiment, the first to m+1-th voltage output circuits output the voltage based on the gradation data to the other end of the first to m+1-th voltage outputting capacitors, and thus the second driving circuit can output the voltage corresponding to the gradation data. The m+1 bit gradation data combining the negative polarity and the positive polarity is obtained by extending the gradation data of m bits by 1 bit, and thus the second driving circuit can output the gradation voltage of the negative polarity and positive polarity.

15 In addition, in this embodiment, a total capacitance of the second feedback capacitor and the first to m+1-th voltage outputting capacitors may be greater than a capacitance of the first feedback capacitor.

20 According to this embodiment, the gain fed back by the voltage change of the output node of the first driving circuit to the inverting input node of the computation amplifier is smaller than $\frac{1}{2}$. As a result, the voltage range fed back to the inverting input node of the computation amplifier is smaller than $\frac{1}{2}$ of the voltage range of the signal supply line. In this manner, the computation amplifier can be composed of a transistor with a breakdown voltage lower than the breakdown voltage of the transistor making up the first driving circuit.

25 In addition, in this embodiment, the driver may further include an m+1-th voltage outputting capacitor including one end electrically coupled to the inverting input node of the computation amplifier; and an m+1-th voltage output circuit configured to output a voltage based on a polarity inversion signal to the other end of the m+1-th voltage outputting capacitor.

30 According to this embodiment, the m+1-th voltage output circuit outputs the voltage based on the polarity inversion signal, and thus the charge based on the polarity inversion signal is output from the m+1-th voltage outputting capacitor to the inverting input node of the computation amplifier. This can reduce the feedback gain from the output node of the first driving circuit to the inverting input node of the computation amplifier, and thus the improvement of the accuracy of the D/A conversion of the second driving circuit and the like can be achieved.

35 In addition, in this embodiment, a distance between a source and a drain of the transistor making up the first driving circuit may be greater than a distance between a source and a drain of a transistor making up the second driving circuit. Alternatively, a film thickness of a gate insulating film of the transistor making up the first driving circuit may be greater than a film thickness of a gate insulating film of the transistor making up the second driving circuit.

40 According to this embodiment, the transistor making up the second driving circuit including the computation amplifier can be composed of a transistor with a breakdown voltage lower than the breakdown voltage of the transistor making up the first driving circuit.

21

In addition, in this embodiment, the first to m-th voltage output circuits may be made up of a transistor with a breakdown voltage lower than the breakdown voltage of the transistor making up the first driving circuit.

In this embodiment, the voltage change fed back to the inverting input node of the computation amplifier is smaller than the power source voltage of the computation amplifier. In this manner, the first to m-th voltage output circuits can be composed of a low-breakdown voltage transistor. The use of a low-breakdown voltage transistor enables faster pixel drive and smaller driver area.

In addition, in this embodiment, the driver may further include an initialization switch configured to be turned on in an initialization period. The initialization switch may supply a reference voltage to the inverting input node of the computation amplifier.

According to this embodiment, after the inverting input node of the computation amplifier is initialized to the reference voltage in the initialization period, it is maintained at the reference voltage through virtual short. In this manner, in the case where the output voltage output by the first driving circuit is shifted from the target voltage, the voltage of the inverting input node of the computation amplifier is shifted from the reference voltage, and this shift is corrected by the computation amplifier so as to set the output voltage to the target voltage.

In addition, in this embodiment, the first driving circuit may include a capacitor driving circuit configured to output first to n-th capacitor drive voltages corresponding to the gradation data to first to n-th capacitor driving nodes, n being an integer of 2 or more, and a capacitor circuit including first to n-th capacitors disposed between the signal supply line and the first to n-th capacitor driving nodes. Here, n is an integer of 2 or more.

According to this embodiment, the capacitor driving circuit outputs the first to n-th capacitor drive voltages corresponding to the gradation data and thus the first to n-th capacitors output the charge of the electric charge amount corresponding to the gradation data to the signal supply line. As a result, the voltage corresponding to the gradation data is output to the signal supply line. Since this driving is not feedback-controlled, errors may be caused between the voltage output through the driving and the target voltage. This error can be corrected by the second driving circuit through a feedback-control.

In addition, this embodiment may further include a control circuit configured to control the first driving circuit. The first driving circuit may include a first driving transistor group disposed between the signal supply line and a node to which a high-potential side power source voltage is supplied, and a second driving transistor group disposed between the signal supply line and a node to which a low-potential side power source voltage is supplied. The control circuit may perform on-off control of each transistor of the first driving transistor group or each transistor of the second driving transistor group based on the gradation data.

According to this embodiment, the transistor of the first driving transistor group or the second driving transistor group that is turned on based on the gradation data outputs the charge of the electric charge amount corresponding to the gradation data to the signal supply line. As a result, the voltage corresponding to the gradation data is output to the signal supply line. Since this driving is not feedback-controlled, errors may be caused between the voltage output through the driving and the target voltage. This error can be corrected by the second driving circuit through a feedback-control.

22

In addition, an electrooptical device of this embodiment includes any of the above-described drivers and an electrooptic panel.

In addition, an electronic apparatus of this embodiment includes any of the above-described drivers.

Although the embodiment has been described in detail above, it will be readily understood by those skilled in the art that many variations are possible that do not materially depart from the novel matters and effects of the present disclosure. Accordingly, all such variations shall be included within the scope of this disclosure. For example, a term that is mentioned at least once in the specification or drawings together with a different term that is broader or synonymous may be replaced by that different term at any point in the specification or drawings. All combinations of the embodiments and variations are also included within the scope of this disclosure. In addition, the configurations, operations, and the like of the control circuit, the data line driving circuit, the driver, the electrooptic panel, the electrooptical device, the electronic apparatus and the like are not limited to the embodiment, and various variations may be made.

What is claimed is:

1. A driver comprising:
a first driving circuit configured to supply a data signal to a signal supply line of an electro-optic panel based on gradation data; and
a second driving circuit including a computation amplifier, an output capacitor, a first feedback capacitor, first to m-th voltage outputting capacitors, and first to m-th voltage output circuits, and electrically coupled to the signal supply line, the computation amplifier being made up of a transistor with a breakdown voltage lower than a breakdown voltage of a transistor making up the first driving circuit, the output capacitor being disposed between an output node of the computation amplifier and the signal supply line, the first feedback capacitor being disposed between an inverting input node of the computation amplifier and the signal supply line, the first to m-th voltage outputting capacitors including one end electrically coupled to the inverting input node of the computation amplifier, the first to m-th voltage output circuits being configured to output a voltage based on the gradation data to the other end of the first to m-th voltage outputting capacitors, m being an integer of 2 or more.
2. The driver according to claim 1, wherein a reference voltage is input to a non-inverting input node of the computation amplifier.
3. The driver according to claim 1, wherein the second driving circuit includes a second feedback capacitor disposed between the inverting input node of the computation amplifier and a predetermined potential node.
4. The driver according to claim 3, wherein the second driving circuit includes:
an m+1-th voltage outputting capacitor including one end electrically coupled to the inverting input node of the computation amplifier; and
an m+1-th voltage output circuit configured to output the voltage based on the gradation data to the other end of the m+1-th voltage outputting capacitor.
5. The driver according to claim 4, wherein a total capacitance of the second feedback capacitor and the first to m+1-th voltage outputting capacitors is greater than a capacitance of the first feedback capacitor.

6. The driver according to claim 3, further comprising: an m+1-th voltage outputting capacitor including one end electrically coupled to the inverting input node of the computation amplifier; and an m+1-th voltage output circuit configured to output a voltage based on a polarity inversion signal to the other end of the m+1-th voltage outputting capacitor. 5
7. The driver according to claim 6, wherein a total capacitance of the second feedback capacitor and the first to m+1-th voltage outputting capacitors is greater than a capacitance of the first feedback capacitor. 10
8. The driver according to claim 1, wherein a distance between a source and a drain of the transistor making up the first driving circuit is greater than a distance between a source and a drain of a transistor making up the second driving circuit, or a film thickness of a gate insulating film of the transistor making up the first driving circuit is greater than a film thickness of a gate insulating film of the transistor making up the second driving circuit. 15
9. The driver according to claim 1, wherein the first to m-th voltage output circuits are made up of a transistor with a breakdown voltage lower than the breakdown voltage of the transistor making up the first driving circuit. 20
10. The driver according to claim 1, further comprising an initialization switch configured to be turned on in an initialization period, and supply a reference voltage to the inverting input node of the computation amplifier. 25

11. The driver according to claim 1, wherein the first driving circuit includes: a capacitor driving circuit configured to output first to n-th capacitor drive voltages corresponding to the gradation data to first to n-th capacitor driving nodes, n being an integer of 2 or more, and a capacitor circuit including first to n-th capacitors disposed between the signal supply line and the first to n-th capacitor driving nodes. 5
12. The driver according to claim 1, further comprising a control circuit configured to control the first driving circuit, wherein the first driving circuit includes: a first driving transistor group disposed between the signal supply line and a node to which a high-potential side power source voltage is supplied, and a second driving transistor group disposed between the signal supply line and a node to which a low-potential side power source voltage is supplied, and the control circuit performs on-off control of each transistor of the first driving transistor group or each transistor of the second driving transistor group based on the gradation data. 10
13. An electro-optical device comprising: the driver according to claim 1; and the electro-optic panel. 15
14. An electronic apparatus comprising: the driver according to claim 1. 20
